UNITED STATES PATENT OFFICE.

JOSEPH STONEBREAKER, OF MCGILL, NEVADA.

SAMPLER.

1,333,191.

Specification of Letters Patent.

Patented Mar. 9, 1920.

Application filed July 22, 1919. Serial No. 312,490.

To all whom it may concern:

Be it known that I, JOSEPH STONEBREAKER, citizen of the United States, residing at McGill, in the county of White Pine and 5 State of Nevada, have invented certain new and useful Improvements in Samplers, of which the following is a specification.

This invention has for its object to provide mechanism whereby samples of ore or other 10 matter may be taken automatically at desired intervals and the value of an average yield thereby determined.

The invention is illustrated in the accompanying drawings, in which—

15 Figure 1 is a side elevation of one embodiment of the invention;

Fig. 2 is an end elevation of the same;

Fig. 3 is an end view of the car appearing in Fig. 1;

20 Fig. 4 is a side elevation of another embodiment of the invention.

In carrying out my invention, I employ a substantial supporting frame 1 which may be of any desired construction and is erected 25 or built at the side of or adjacent the flowing stream of material to be sampled. Upon this supporting frame is journaled a longitudinal drive shaft 2 equipped at one end with a band pulley 3 which may be driven 30 from any convenient or preferred prime motor and in Fig. 2 is illustrated as connected by a belt 4 with a driving pulley 5. Upon the shaft 2 between the center and the ends thereof, I secure or form worm 6 35 which have their threads oppositely disposed, as clearly shown in Fig. 1. These worms mesh with worm gears 7 and 8 which are mounted loosely upon shafts 9 suitably journaled upon the supporting frame and

40 each worm gear is provided on one face with a lateral lug 10 adapted to impinge against a similar lug 11 on the opposed face of a wheel or disk 12 which is fixed upon the shaft adjacent the worm gear. The 45 wheel 12 is provided on its periphery with a cam or projection 13 and also carries a weight 14 upon one of its spokes and on one end of each shaft 9 is secured an arm 15 having a weight 16 adjustably fitted 50 thereon. The weights 14 and 16 act in unison but are disposed upon different radii of the shaft so that they will overcome all dead centers and the operation of the machine will be certain at all times. Fully 55 crummed upon the supporting frame, midway

between the two shafts 9 and above the horizontal plane of the same, is a shaft or rod 17 upon which is mounted a lever 18, the lower end of the lever being equipped with a roller 19 which is adapted to be engaged 60 by the projections or cams 13 of the two wheels alternately and the upper end of the lever being connected by a pitman 20 with a sampling car 21. It will be noted upon reference to Fig. 1 that the upper arm of 65 the lever is very much longer than the lower arm thereof so that the throw of the lever will be amplified and the car 21 moved a sufficient distance to pass across the stream from which the sample is taken. In Fig. 1 70 the car is illustrated as arranged to pass across the stream and is mounted upon an arched track 22 so that when the car has moved over the crown or apex of the track, which should preferably be at the center of 75 the stream, the incline of the track will aid in holding the car in the position to which it has moved until the driving mechanism again positively acts on the car to return it to its initial position.

80 The car consists of a wheeled frame from which depend hangers 23 to the lower ends of which is secured a chute 24 having a hopper 25 at its upper end and having its lower end playing over and discharging into 85 a trough or receiving hopper 26. The element 26 may be a container in which the material will be held until removed by any convenient means or it may be the mouth 90 of a storage receptacle into which the material will flow automatically but, in any event, it should have an open top of such length that the chute will be over the same in all its positions.

95 The operation of the machine will, it is thought, be readily understood. The vibrating lever is mounted in the vertical plane of the wheels 12 which are secured on the respective shafts 9 while the worm gears 7 and 8, as stated, are loosely fitted upon the 100 shafts and rotated in opposite directions. The lugs 10 upon the respective worm gears are arranged upon different radii of the respective shafts 9 and the projections 13 upon the wheels 12 are so arranged that the projection on one wheel cannot engage the roller 19 upon the lever at the same time that the roller is engaged by the projection or cam upon the other wheel. Assuming 105 that the shaft 2 is rotating, the worm gears 110

7 and 8 will be turned in opposite directions about the respective shafts 9 but the wheels 12 will normally be at rest. As the lug 10 upon the gear 7, for instance, comes 5 into contact with the lug 11 upon the adjacent wheel 12 it will transmit motion to the said wheel and the shaft 9 so that the weights 14 and 16 will be raised. As soon as the weights pass beyond the vertical 10 plane of the shaft 9 they will immediately begin to drop and will accelerate the motion of the wheel 12, the lug 11 leaving the lug 10 and the cam or projection 13 being carried quickly into engagement with the roller 19 upon the lever 18 and riding on and past 15 the same so that the lever will be quickly swung from the position shown in full lines to the position shown in dotted lines in Fig. 1. The car 21 will, of course, be moved 20 across the stream and will remain in the position to which it is thus moved until the cam or projection 13 upon the wheel 12 co-operating with the worm gear 8 is brought 25 into engagement with the roller 19, whereupon the lever will be given a reverse oscillation and the car returned to its initial position. The speed of the worm gears is steady and uniform but it will be readily noted that the lever-actuating wheels or 30 disks move rapidly when acting upon the lever but move more slowly between the actuating periods, the movement during the actuating period being due to the gravitating force of the weights 14 and 16 while 35 the intervening movement is due to the engagement of the lug 10 of the worm wheel with the lug 11 on the lever-actuating wheel. I thus move the car across the stream rapidly so that there will be no choking of the 40 same and then provide an interval of rest for the car so that the samples will be taken at regular periods and an average value ascertained. By properly regulating the speed of the driving shaft 2, the periods 45 intervening between the taking of samples may be lengthened or shortened as desired.

The arm 15 with its weight 16 constitutes a pendulum having a tendency to oscillate in both directions when once set in motion. 50 To arrest the pendulum and prevent backward movement thereof which would result in damaging contact between the lugs 10 and 11, I provide the racks 27 below and concentric with the pendulums having teeth 28 55 on their upper sides and on the ends of the arms 15 are dogs 29 which will ride over the teeth 28 in the forward movement of the pendulum but will engage against one of the teeth when the pendulum attempts to 60 swing backward. The pendulum will consequently be held at the upper limit of its forward movement until the lugs 10 and 11 are again properly engaged.

In Fig. 4 I have illustrated an arrangement 65 which is especially adapted for use

under conditions which require that the car move endwise into the stream or bank from which a sample is to be taken, it being evident that it is necessary in such event for the car to be immediately withdrawn. In 70 this arrangement, the lever 30 corresponds in all respects with the lever 18 and is connected by a pitman 31 with the car 32. That section of the machine which is shown at the right in Fig. 1, however, will be 75 omitted and only one section employed, the operation of the section being to drive the car into the bank. To withdraw the car from the bank, I erect a post or anchor 33 adjacent the bank and extend a cable 34 between the upper end of the post and the end of the car, a weight 35 being hung on the cable, as shown. The car will be driven into the bank by the machine and the lever is then left free, whereupon the weight 35 80 immediately drops and withdraws the car from the bank, it being understood that when the car is pushed into the bank by the action of the lever the cable tends to straighten so that the weight 35 will be 85 lifted. The chute 36 is supported by hangers 37 from the car body but is arranged longitudinally thereof instead of transversely as in Fig. 3, the upper end of the chute projecting beyond the adjacent 90 end of the car, and the lower end of the chute discharging into a hopper 38.

My improved machine is simple in the construction and arrangement of its parts and can be installed and operated at a low 100 cost. When in operation it will be positive in its action and certain in its results.

Having thus described the invention, what is claimed as new is:

1. In a sampling machine, the combination of a sampling car, an oscillating lever operatively connected with the car, an actuating wheel arranged to engage the lever, and means for periodically moving the said wheel rapidly to act upon the lever and slowly returning it to the actuating position. 105
2. In a machine for the purpose set forth, the combination of an oscillating lever, an actuating wheel arranged adjacent the lever and constructed to engage the same, 115 mechanically operative means for turning the wheel through a part of a revolution whereby to bring it into position to act upon the lever, and means for automatically turning it beyond said position to actuate the 120 lever.
3. In a sampling machine, the combination of a vibratory lever, a shaft mounted adjacent the lever, a wheel secured on said shaft and having a cam to engage the lever, 125 gravitating means acting upon the shaft and the wheel to move said wheel across the path of the lever and thereby vibrate the lever, and a constantly rotating member mounted loosely upon the shaft and constructed to 130

engage said actuating wheel periodically to move it in opposition to the said gravitating means.

4. In a sampling machine, the combination of a vibratory lever, an actuating wheel loosely mounted adjacent the lever and provided with a peripheral projection to act thereon, gravitating means arranged to carry said wheel rapidly across the path of the lever whereby said projection will engage and actuate the lever, a member moving continuously at a uniform speed adjacent said actuating wheel, and interengaging means on said member and the actuating wheel whereby said wheel will be periodically moved in opposition to said gravitating means.

5. In a sampling machine, the combination of a vibratory lever, a shaft mounted adjacent said lever, an actuating wheel secured on said shaft, a peripheral cam on said wheel adapted to engage the lever, a weight on the wheel, a cooperating weight on the shaft, means coöperating with the last-mentioned weight to prevent backward movement of the actuating wheel, a lateral projection on one face of the wheel, a gear mounted loosely on the shaft adjacent the actuating wheel, and a projection on the face of said gear adapted to engage the lateral projection on the actuating wheel.

- 30 6. In a sampling machine, the combina-

tion of a vibratory lever, a shaft mounted adjacent said lever, an actuating wheel secured on said shaft, a peripheral cam on said wheel adapted to engage the lever, a weight on the wheel, a cooperating weight 35 on the shaft, means coöperating with the last-mentioned weight to prevent backward movement of the actuating wheel, a lateral projection on one face of the wheel, a gear mounted loosely on the shaft adjacent the 40 actuating wheel, and a projection on the face of said gear adapted to engage the lateral projection on the actuating wheel.

7. In a sampling machine, the combination of a vibratory lever, a shaft mounted 45 adjacent the lever, a wheel secured on said shaft and having a cam to engage the lever, gravitating means acting upon the shaft and the wheel to move said wheel across the path of the lever and thereby vibrate the lever, a 50 constantly rotating member mounted loosely upon the shaft and constructed to engage said actuating wheel periodically to move it in opposition to the said gravitating means, and means for holding the actuating wheel 55 at a limit of its movement against backward movement between successive periods of its actuation.

In testimony whereof I affix my signature.

JOSEPH STONEBREAKER. [L. s.]
